Specification for Design.

Patented June 15, 1920.

Application filed November 22, 1919. Serial No. 339,953. Term of patent 7 years.

To all whom it may concern:

Be it known that I, MAURICE E. HARRIS, a citizen of the United States, residing at Chicago, in the county of Cook and State of Illinois, have invented a new, original, and ornamental Design for Playing-Cards, of which the following is a specification, reference being had to the accompanying draw-

ing, forming part thereof, which exhibits in plan view a card embodying the ornamental showing of my new design.

I claim:

The ornamental design for a playing card, substantially as shown.

MAURICE E. HARRIS.
